United States Patent Office

Des. 197,407
Patented Jan. 28, 1964

197,407

MUG

Clayton A. Laughlin, Minneapolis, Minn., assignor to Arthur Salm Inc., Chicago, Ill., a corporation of Illinois

Filed May 21, 1963, Ser. No. 74,993

Term of patent 14 years

(Cl. D44—9)

FIG. 1 is a top plan view of a mug showing my new design;

FIG. 2 is an end view thereof;

FIG. 3 is a perspective view thereof; and

FIG. 4 is a front view thereof.

I claim:

The ornamental design for a mug, substantially as shown.
